(57) **CLAIM**

The ornamental design for an automobile taillight, as shown and described.

DESCRIPTION

FIG. 1 is a perspective view of an automobile taillight;
FIG. 2 is a front view thereof;
FIG. 3 is a left side view thereof; and,
FIG. 4 is a top side view thereof. The broken lines are
included to show environmental structure and form no part
of the claimed design. The drawings and descriptions rep-
resent the left side embodiment. The claim is also for a
mirror image right side embodiment.
